UNITED STATES PATENT OFFICE.

DAVID BAKER, OF PHILADELPHIA, PENNSYLVANIA.

FURNACE-CHARGING MECHANISM.

No. 830,958.

Specification of Letters Patent.

Patented Sept. 11, 1906.

Application filed March 23, 1906. Serial No. 307,628.

To all whom it may concern—

Be it known that I, DAVID BAKER, of Philadelphia, county of Philadelphia, and State of Pennsylvania, have invented a new and useful Improvement in Furnace-Charging Mechanism, of which the following is a specification.

This invention relates to mechanism for charging blast-furnaces; and the invention has in view the even and uniform distribution of the stock in the furnace, to the end that there will be no sorting or separation of the lumps and fine ore and the stock will be charged into the furnace in the condition most favorable for effective and uniform working.

The invention comprehends a distributing mechanism of improved form and construction which acts to receive the charging materials from the source of supply, usually the skip-cars, and which operates to direct the successive skip-loads to different points around the main hopper on the main distributing-bell, so that when the latter is opened to discharge the contents of the main hopper into the furnace the different loads of material will enter the furnace in the distributed relations they occupied in the main hopper.

In its more specific form my improved distributing mechanism comprehends in combination with the main hopper and its distributing-bell a rotary receiving hopper or chamber and a rotary deflecting plate or shield movable around with and by the rotary hopper, which plate serves to direct the materials entering the receiving-hopper to one side of the main hopper and which plate by its rotary motion serves to vary the point of entrance of the materials into the main hopper, means being provided, in the present instance a gas-seal bell connected with the deflecting-plate, for closing the bottom of the receiving-hopper against the escape of gases when the main bell is opened.

In the accompanying drawings, Figure 1 is a sectional elevation of the upper portion of a blast-furnace having my invention applied thereto. Fig. 2 is a side elevation of the same as viewed in the direction of the arrow in Fig. 1. Fig. 3 is a horizontal sectional plan view looking downward on the line *a—a* of Fig. 1. Fig. 4 is a perspective view, on an enlarged scale, of the deflecting-plate and the attached gas-seal bell removed from the receiving-hopper. Fig. 5 is a vertical sectional elevation, on an enlarged scale, through the

receiving-hopper, showing the position of the deflecting-plate and gas-seal when the main hopper is closed and when the stock is charged into the receiving-hopper.

Referring to the drawings, 1 represents the upper part of a blast-furnace formed with the usual main hopper 2, closed at its lower end by the main distributing-bell 3, carried on the lower end of a vertical stem or rod 5, which by suitable mechanism is moved up and down to raise and lower the bell, and thus control the communication of the main hopper with the interior of the furnace. Any suitable mechanism may be employed for operating the main bell; but I have illustrated in the drawings a common and well-known mechanism for this purpose. It consists of a controllable power-cylinder 6, having its piston connected, by means of a vertical rod 7, with the outer end of a horizontal operating-lever 8, pivotally supported between its ends on the superstructure of the furnace and having its inner end jointed to the upper end of the stem 5.

The main hopper is closed at its upper end by a cover-plate 9, containing a central circular opening through which loosely extends, so as to rotate therein, the lower end of a cylindrical receiving hopper or chamber 10, having its upper end open and adapted to receive the loads of charging material from the source of supply, in the present instance skip-cars 11.

The receiving-hopper is provided about midway between its ends with a horizontal annular flange 12, having its inner under side smooth and seated on the upper horizontal surface of a supporting-ring 14, sustained on uprights rising from the cover-plate, by which means the hopper is held in an upright position in such manner that it may be rotated on the supporting-ring by the mechanism presently to be described.

Situated in the receiving-hopper and movable vertically therein is an inclined deflecting-plate 15 of a form and size to extend partially across the hopper, the edge of the plate being curved to conform to the interior of the hopper in an oblique plane. This plate receives the stock entering the hopper and directs it to one side into the main hopper, and it is so connected operatively with the receiving-hopper that while being capable of a limited vertical motion relatively to it the plate

will be compelled to move around with the receiving-hopper, by which rotary motion the point of discharge of the materials into the main hopper may be varied. The connection of the plate with the receiving-hopper, by which this action is effected, is in the form of a vertical inwardly-extending rib 16 on the interior of the receiving-hopper extending loosely in a notch 17 in the edge of the deflecting-plate, the engagement of the rib in the notch acting to move the plate around with the hopper while at the same time allowing the plate to be moved vertically with relation to the hopper.

15 The deflecting-plate has fixed to its lower end a gas-seal in the form of a conical plate or bell 18, the purpose of which is to close the lower end of the receiving-hopper against the escape of gases when the main bell is lowered 20 to discharge the contents of the main hopper into the furnace. This gas-seal bell co-operates with the lower end of the receiving-hopper in such manner that when it is held up against the bottom of the hopper it will effectually close the same, but when lowered away from the bottom of the hopper it will leave a free space for the discharge of the charging materials from the surface of the deflecting-plate laterally through the bottom 25 of the receiving-hopper and into the main hopper, the upper surface of the gas-seal bell being inclined and forming a continuation of the inclined plate, so as to facilitate the fall of the materials and insure their lateral discharge into the main hopper.

30 The deflecting-plate is carried on the lower end of a tubular stem 20, inclosing the stem 5 of the main bell and having its upper end suspended rotatably from the inner end of a horizontal lever 21, pivotally supported between its ends, as at 22, on the superstructure of the furnace, and having its outer end jointed to the upper end of a vertical rod 23, connected with the piston 24 of a power-cylinder 25. The arrangement is such that on 35 the rise of the piston the inner end of the operating-lever will be lowered and will lower the deflecting-plate and gas-seal carried thereby, leaving an unobstructed passage from the receiving-hopper to the main hopper, which is the position of the parts when the load of material from the skip-car is dumped into the receiving-hopper. When the piston moves downward, the inner end of the operating-lever will be raised and will draw the gas-seal up against the lower end of the receiving-hopper, which is the position of the parts when the main bell is lowered to discharge 40 the contents of the main hopper into the furnace. I propose to utilize this operating mechanism as a means for rotating the receiving-hopper, and thus change the position of the deflecting-plate. This I accomplish by providing a horizontal shaft 26, mounted in 45 bearings 27 on the top of the furnace, which

50 shaft carries at its inner end a driving-pinion 28, meshing with gear-teeth 29 on the under side of the annular flange 12 on the receiving-hopper. The shaft is provided with a driving ratchet-wheel 29^a, fixed thereto, which is engaged by a pawl 30 on a horizontal vibrating lever 31, having its inner end mounted loosely around the shaft and having its outer end jointed to the lower end of a vertical rod 32, the upper end of which is jointed to the 55 operating-lever 21 at a point inward of its pivotal axis 22. The relation of the pawl 30 to the teeth of the ratchet-wheel is such that the pawl will engage and turn the wheel, and consequently the driving-pinion, when the 60 vibrating lever moves upward, which action takes place when the gas-seal bell is raised. When the vibrating lever descends on the lowering of the gas-seal bell, the pawl clicks over the teeth of the ratchet-wheel, and the latter remains at rest. It is seen, therefore, that by means of the driving mechanism described the deflector-plate may be rotated to change the direction of discharge by raising the gas-seal bell, which action will rotate the 65 hopper, and this in turn, through the medium of the rib and notch, will rotate the deflector-plate.

70 In the operation of the mechanism the skip-cars discharge their contents into the receiving-hopper while the gas-seal bell is in its lower open position, and the charge passes laterally from the inclined surface of the deflector-plate directly into the main hopper at one side. Power-cylinder 25 is now operated 75 to raise the gas-seal bell in order to close the lower end of the receiving-hopper against the escape of gases. This raising action of the bell automatically and by means of the mechanism described rotates the receiving-hopper a partial turn, and through its engagement with the deflector-plate the latter is turned with it and takes a different position. Power-cylinder 6 is now operated to lower the main distributing-bell 3, and the 80 charge which had been introduced into the main hopper passes into the furnace. The main bell is closed again and power-cylinder 25 operated to lower the gas-seal in order to open the lower end of the receiving-hopper 85 for the next charge. The next skip-car now discharges its load into the upper end of the receiving-hopper, and the charge is directed by the deflector-plate in its changed position laterally through the lower end of the receiving-hopper into the main hopper, but at a 90 different point from the previous charge. These operations are continued, resulting in the distribution of the successive charges into the furnace at different points therearound. 95

100 Instead of discharging each load successively from the main hopper into the furnace, the mechanism may be operated to deposit in the main hopper its full and complete charge, after which the main bell may be 105

opened to enter the entire charge into the furnace. In proceeding in this manner the gas-seal bell would be raised and lowered as before between each skip-load in order to change the position of the deflector-plate, and after it had been thus operated to deposit the successive skip-loads around at intervals in the main hopper the main bell on being opened would permit the entire charge in the main hopper to enter the furnace.

It will be observed that in the mechanism described the sole function of the gas-seal bell is to seal the receiving-hopper against the escape of gases when the main bell is opened. The gas-seal bell does not at any time act to retard the passage of the materials into the main hopper; but, on the contrary, the charging materials pass directly into the main hopper from the receiving-hopper, which is open at its lower end when the skip-cars dump their loads into the upper end. It will also be observed that the vertical movements of the gas-seal bell are utilized to change the position of the deflector-plate through the medium of the receiving-hopper, which is given a rotary motion when the bell rises and which by its engagement with the deflector-plate imparts its rotary motion thereto. This I deem of great importance and advantage, in that the turning movement of the plate is applied to its periphery, at which point less power is required than if the turning force were applied at the center of the plate. It will be observed, further, that when the hopper is rotated in order to effect the rotation of the deflector-plate the former is empty, so that much less power is required to perform this action than if the hopper were turned with its load confined therein by a closure.

Owing to the fact that there is no closure for the receiving-hopper the materials are never accumulated therein, but pass directly through it into the main hopper. Under these circumstances the capacity of the receiving-hopper need not be even such as to hold a single skip-load, the receiving-hopper acting, in effect, merely as a chute to receive the materials from the cars and guide or direct the same directly into the main hopper. This action greatly reduces the liability of breakage of the coke, which in some regions is very soft and friable, so that the loss is reduced to a minimum.

It is manifest, of course, that other means than the power-cylinder and the parts operated thereby may be employed for raising and lowering the gas-seal bell, the essence of the invention in this respect residing in utilizing the power which may be employed for this purpose in giving a rotary motion to the receiving-hopper and in transmitting this rotary motion from the receiving-hopper to the deflector-plate at a point beyond the axis around which it turns.

Having thus described my invention, what I claim is—

1. In combination with a furnace, a rotary receiving-hopper, a deflector-plate movable vertically with relation to the hopper, operative connections between the plate and the hopper whereby the plate will be moved around with the hopper, and means for rotating the hopper.

2. In combination with a furnace, a rotary receiving-hopper, a deflector-plate therein movable vertically with relation to the hopper, a gas-seal carried by the plate and adapted to close the lower end of the hopper, means for rotating the hopper, and a connection between the hopper and plate for rotating the latter with the hopper.

3. In combination with a furnace, a rotary receiving-hopper, a deflector-plate situated in the hopper and slidably interlocked therewith, and means for rotating the hopper.

4. In combination with the furnace, a rotary receiving-hopper, a deflector-plate therein, one of said parts being formed with a vertical rib extending loosely in a notch in the other part; whereby the plate may be moved relatively to the hopper vertically, and whereby the plate will be caused to rotate with the hopper, and means for rotating the hopper.

5. In combination with a furnace, a rotary receiving-hopper formed on its interior with a vertical rib, a deflector-plate situated in the hopper and provided with a notch in which the rib loosely engages, and means for rotating the hopper.

6. In combination with a furnace, a rotary receiving-hopper, a deflector-plate situated therein and movable vertically, operative connections between the plate and the hopper for turning the plate, means for moving the plate vertically, and means controlled by the vertical movement of the plate for rotating the hopper.

7. In combination with a furnace, a rotary receiving-hopper, a deflector-plate situated therein and movable vertically, a gas-seal carried by the plate and adapted to coöperate with the lower end of the hopper, means for moving the plate vertically, means controlled by the vertical movement of the plate for rotating the hopper, and connections between the plate and hopper for imparting the rotary motion of the hopper to the plate.

8. In combination with a furnace, a main hopper and distributing-bell, a rotary receiving-hopper surmounting the main hopper, a deflector-plate in the receiving-hopper movable vertically with relation to the same, a gas-seal carried by the plate and adapted to coöperate with the lower end of the receiving-hopper, a connection between the hopper and plate for turning the latter, and means for rotating the hopper.

9. In combination with a furnace, a rotary receiving-hopper communicating with the

5 interior of the furnace, a deflector-plate situated in the hopper adapted to direct the stock entering the hopper to one side and movable vertically with relation to the hopper, a gas-seal adapted to close the communication of the receiving-hopper with the interior of the furnace, means for rotating the hopper, and a connection between the hopper and plate for rotating the latter with the

10 hopper.

10. In combination with a furnace, a rotary receiving-hopper, a deflector-plate movable vertically with relation to the hopper and adapted to direct the stock entering the
15 hopper to one side, operative connections between the plate and the hopper, means for

rotating the hopper, a main hopper below the receiving-hopper and communicating therewith, a gas-seal carried by the deflector-plate and adapted to control the communication of the receiving-hopper with the main hopper, and a bell controlling the communication of the main hopper with the interior of the furnace.

In testimony whereof I hereunto set my hand, this 9th day of March, 1906, in the presence of two attesting witnesses.

DAVID BAKER.
